UNITED STATES PATENT OFFICE.

JOHN EDWARD THORNTON, OF WEST HAMPSTEAD, LONDON, ENGLAND.

MULTICOLOR SCREEN AND SUPPORT FOR FILMS AND PLATES.

Application filed March 24, 1926, Serial No. 97,137, and in Great Britain March 31, 1925.

This invention relates to the manufacture of multi-color screens and film-material for the production of negatives of the multi-color screen type, and is applicable to thin flexible films for roll-film camera-cartridges and film-packs, also for thick stiff flat films, rigid glass plates, and for continuous kinematograph film.

It provides an improved method of constructing and manufacturing the color-screen attached to the transparent support, upon which screen the sensitive panchromatic gelatino-silver-bromide emulsion is eventually superimposed.

Hitherto such screens have been very expensive to produce, but the present invention provides a simpler, more reliable, and cheaper method of manufacture than the methods hitherto known and used.

20 Previous methods of color-screen manufacture.

One well-known system at present in use comprises a screen formed of starch-grains, dyed in lots of three different colors, then mixed and scattered upon a sticky plate, the transparent gaps between the colored grains afterwards being filled with black. In other variations of this system other materials are used for the colored grains.

There are numerous other methods of preparing colored screens, but they are generally upon one principle, differing only in details or methods of printing, the principle consisting in printing by photographic or by mechanical methods, dots, lines, mosaic or other patterns upon a colloid layer or layers attached to the support, or in dyeing the support or the colloid layer to the desired pattern by several operations. In all these methods of forming a three-color screen the difficulty is to secure correct registration of the color-elements and to avoid overlapping; and to thus ensure filling of the entire surface with colors presents great complexity in the manufacturing processes, and entails the need for much expensive skilled labour, and involves considerable wastage to obtain a comparatively small output.

50 The present invention.

The present invention obviates all these objections by forming the screen in two parts, upon two very thin supports, and then superimposing and cementing the two parts

together to form a single film-base or support. Each part is easy to manufacture because no registration is required, and two such parts, each containing different colors, form when cemented together a single compound-support ready to be coated with a sensitized layer of emulsion upon one of the outer surfaces.

The supports upon which the screens are formed may be of any suitable material. For flexible films such as used in roll-film cameras, film-packs, kinematograph apparatus and the like, the two thin films are of celluloid, cellulose-acetate, or similar transparent water-proof material of slightly less than half standard thickness, so that when cemented together they will be approximately the usual standard thickness.

For convenience of manufacture, and to avoid mistakes later, it is preferred to form both parts of the same filter-screen side-by-side upon a double-width strip of film support, or several such double strips may be formed upon a wide web which is eventually divided into double strips after finishing.

The designs forming the screens can be produced by various well-known printing or coloring processes and no claim is made pertaining to any such process.

The designs may be made up as lines, dots, or any other pattern that will produce a mosaic of suitable character and degree of fineness. For kinematograph films one convenient pattern comprises a series of fine lines running longitudinally of one thin film and transversely of the other thin film. Another design comprises lines running diagonally upon each thin film, or diagonally upon one and longitudinally or transversely upon the others. The object in both arrangements is to produce a crossing of the lines when the two thin films are cemented together. The object is to have a design that avoids necessity for any registration of the printing or parts of the design in the process of manufacturing the screen and support, and this is attained by printing half the lines upon one support and crossing them by other lines printed upon the other support.

No claim is made for any particular pattern or design.

Having produced upon each thin film a design or part of a design which constitutes part of a screen, the next step consists in applying an adhesive of known description to the two printed sections, then superimposing

them printed-face to printed-face. Upon the application of heat and pressure the two sections become indissolubly united and form a single support containing the colored screen within its interior. If desired the two parts may be united back-to-back, or back-to-face, but as this separates the two parts of the screen to a greater degree it is not preferred.

10 The next step is to coat the screen-film (which now becomes the film support or base) with the usual adhesive substratum upon one side and follow by superimposing thereon the usual layer of panchromatic 5 gelatino-silver-bromide or other emulsion.

15 In order to ensure that the finished film will lie flat during development the reverse side of the film may be also coated with the adhesive substratum and then with a layer of 20 plain gelatine, generally termed the "non-curling layer."

25 In applying the invention to the manufacture of rigid glass plates, or to films formed of very thick celluloid, it is not advisable to use two such thick supports, as in the single plate or film thus formed the sensitive emulsion would be separated from its color-screen by too great a thickness. This difficulty is therefore overcome by one 30 of the screens being formed directly upon the thick plate or film (or alternatively upon an exceedingly thin tissue or transfer applied and attached thereto), the second screen being formed upon an exceedingly 35 thin film-tissue or transfer applied and attached to the first, so that both are attached to the one support, and the adhesive substratum and emulsion are then applied on top of the combined screens attached to the 40 one thick support.

45 In order that the invention may be fully understood it is illustrated in the accompanying drawings in which Figs. 1 and 2 show two arrangements of four-color screens built up from two half-screens, Figs. 3 and 4 show two arrangements of three-color screens built up from two half-screens, Figs. 5 and 6 show further arrangements of multi-color screens built up from two half-screens, 50 Fig. 7 shows another arrangement of four-color screen built up from two half-screens in which the lines run diagonally on each screen, Fig. 8 is another arrangement of four-color screen built up from two half-screens in which the lines on one screen are 55 diagonal and on the other screen are longitudinal or transverse. Fig. 9 is a perspective view of a strip of kinematograph film-support formed in accordance with the invention, Fig. 10 is a section of same, Fig. 11 is a section of a camera film with a non-curling gelatine layer on the back thereof, Fig. 12 is a section of a relative thick support of non-flexible or non-rollable type such as 60 glass plates very thick celluloid, Fig. 13

is a perspective view of a strip of kinematograph film support formed in accordance with the invention in which the two films are united back to back and Fig. 14 is a perspective view of a strip of kinematograph film support formed in accordance with the invention in which the two half screens are united back to face.

65 The four-color screen shown in Fig. 1 is built up from two half-screens, one of which contains the complementary pair of colors red and blue-green, and the other contains the complementary pair of colors yellow and violet, the colors in each pair being exactly complementary to each other; producing 70 when the two half-screens are superimposed and cemented together, in a crossed position, a support and screen comprising the following colors:—Orange, blue-violet, green and red-violet.

75 The four-color screen shown in Fig. 2 is built up from two half-screens, one of which contains the complementary pair of colors, red and green crossed by the complementary pair of colors, blue and yellow in the other 80 half-screens producing a finished support and screen comprising the following colors:—Violet, orange, yellow-green and blue-green.

85 One arrangement of a three-color screen, built up from the half-screens is shown in Fig. 3, one half-screen contains red and yellow close together, and crossed by the other containing the single color blue separated by uncolored spaces; producing when the two half-screens are superimposed and cemented together with the blue crossing the red and yellow a support and screen comprising the following colors:—Red, yellow, violet and green.

90 A similar arrangement of a three-color screen built up from two half-screens is shown in Fig. 4; one half-screen contains red and yellow-green, crossed by the other containing the single color blue separated by uncolored spaces; producing a finished support and screen comprising the following colors:—Red, yellow-green, violet and blue-green.

95 In the three-color groups Figs. 3 and 4 the pair of colors are not exactly complementary, as is the case in the four-color groups.

100 Fig. 5 shows an arrangement of a multi-color screen built up from two two-colored half-screens, one half-screen containing the colors red and green close together and crossed by the other half-screen containing the colors yellow and blue separated by uncolored spaces; producing a finished support and screen containing the following colors:—Orange, yellow-green, red, green, violet and blue-green.

105 A similar arrangement of a multi-color screen built up from two two-color half-screens is shown in Fig. 6, one half-screen contains the colors red and blue and is

crossed by the other half screen containing the colors yellow and violet separated by uncolored spaces; thus producing a finished support and screen comprising the following 5 colors:—Orange, green, violet-red, violet-blue, red and blue.

In the arrangement shown in Fig. 7 the screen is built up from two two-color half screens, one half screen containing the colors 10 red and blue and the other the colors yellow and violet as in Fig. 1 but the lines of color on each half screen are arranged diagonally.

In the arrangement shown in Fig. 8 the screen is built up from two two-color half 15 screens, one half screen containing the colors red and blue and the other the colors yellow and violet as in Fig. 1, but the lines of color of one screen are arranged diagonally and on the other either vertically or trans- 20 versely.

Figs. 9 and 10 show a kinematograph film produced according to the invention, being built up of two thin celluloid layers forming the support each bearing a half-screen layer, 25 the two thin films, which are each half-supports, being cemented together with the screens inside. There is thus formed a single support of the flexible-film type, upon one side of which is then coated first an adhesive 30 substratum and then a sensitive layer of panchromatic gelatino-silver-bromide emulsion.

There is thus produced a flexible or rollable film of any size or width such as employed 35 for roll-film cameras, for film-packs, or for kinematograph film-ribbons.

Fig. 11 shows a similar film one face of which is coated with an adhesive substratum and then a sensitive layer of panchromatic 40 gelatino-silver-bromide emulsion, and the other face with a layer of gelatine on the back, of the same thickness as the layer of emulsion on the other face, thus forming a non-curling film suitable for roll film 45 cameras and film packs for such as a non-roll camera film.

In Fig. 12 the invention is illustrated as applied to thicker supports of the non-flexible or non-rollable description, such as glass 50 plates or very thick stiff celluloid films. One half the screen is formed upon such thick support, the other half being formed upon an extremely thin support of celluloid (as in Figs. 9 and 10) which is cemented to 55 the stiff half of the support, with the screens inward. The face of the celluloid is next coated with an adhesive substratum and finally with a panchromatic emulsion as described with reference to Figs. 9 and 10.

Instead of the two half screens being united together face to face as shown in Figs. 9 and 10, they may be united back to back as shown in Fig. 13 or back to face as shown in Fig. 14.

65 The approximate thickness of the various

layers of the film illustrated in Figs. 9 to 14 are as follows:—For the films—

Each celluloid layer $\frac{1}{1000}$ inch thick.

Each screen layer $\frac{1}{5000}$ inch thick.

Each cement layer $\frac{1}{10000}$ inch thick, these 70 three layers duplicated forming a complete flexible support.

One substratum layer $\frac{1}{10000}$ inch thick.

One emulsion layer $\frac{1}{10000}$ inch thick these latter being applied to one of the outer faces 75 of the flexible support.

Where a non-curling film is required the other face is provided with:—

A substratum layer $\frac{1}{10000}$ inch thick.

A gelatine layer $\frac{1}{10000}$ inch thick.

For thick rigid films the celluloid is $\frac{1}{100}$ inch thick and for glass plates the glass is about $\frac{3}{2}$ inch thick, the other layers remaining the same.

All the above figures are approximate and 85 may be varied as required.

What I claim as my invention and desire to protect by Letters Patent is:—

1. A multi-color-screen and support to carry a sensitive layer for the production of 90 photographic and kinematograph pictures comprising two half screens and two supports (one for each half screen), the completed screen being formed by cementing the two parts together thus forming a compound 95 screen upon a compound support which is capable of being subsequently sensitized in the usual manner.

2. A multi-color-screen film for photographic and kinematograph pictures comprising 100 two half-screens and two supports (one for each half-screen), the completed screen being formed by cementing the two parts, an adhesive substratum applied to one side of the compound support and a sensitive 105 layer applied to the substratum.

3. A multi-color screen film for photographic and kinematograph pictures comprising two half-screens and two supports, (one for each screen), the completed screen 110 being formed by cementing the two parts, an adhesive substratum applied to one side of the compound support, an adhesive substratum applied to the other side of the compound support, a sensitive layer applied to 115 one adhesive substratum and a non-sensitive colloid layer applied to the other substratum on the other side of the compound support.

4. A multi-color screen plate for photographic purposes comprising two half- 120 screens, a thin flexible support for one half-screen, a stiff support for the other half-screen, the completed screen being formed by cementing the two parts together, an adhesive substratum applied to the face of the 125 thin support and a sensitive layer applied to the substratum.

In testimony whereof I have hereunto set my hand.

JOHN EDWARD THORNTON.
